CLAIM

The ornamental design for a school bus-simulating lighting fixture, as shown and described.

DESCRIPTION

FIG. 1 is a top-side perspective view of a school bus-simulating lighting fixture showing my new design;

FIG. 2 is a front elevational view;

FIG. 3 is a left side elevational view thereof, the opposite side being plain and unornamented;

FIG. 4 is a rear elevational view thereof;

FIG. 5 is a top plan view thereof; and,

FIG. 6 is a bottom plan view.

The portions of the drawings provided by broken line are intended to reflect environment, and do not form a part of the indicated embodiment of my design.
